By Attorney

UNITED STATES PATENT OFFICE.

CHARLES C. S. EPHRAIM, OF NEWCASTLE, NATAL, SOUTH AFRICA.

FENCE-POST.

1,264,624.

Specification of Letters Patent. Patented Apr. 30, 1918.

Application filed December 6, 1916. Serial No. 135,415.

To all whom it may concern:

Be it known that I, CHARLES C. S. EPHRAIM, a subject of the King of Great Britain, residing at Newcastle, in the 5 Province of Natal, South Africa, have invented certain new and useful Improvements in Fence-Posts; and I do hereby declare the following to be a full, clear, and exact description of the invention, such as 10 will enable others skilled in the art to which it appertains to make and use the same.

This invention has for its object to provide an improved metallic fence post and locking plate associated therewith to fasten 15 the fence wires in position without the use of staples or similar fastening devices.

Another object is the provision of an improved fence post including a body member and head formed integral therewith and 20 projecting laterally of one longitudinal edge thereof and constituting a reinforcing element, and also designed to assist in rigidly supporting or anchoring the post in position in the ground.

25 With these and other objects in view, the invention consists in the novel construction, combination and arrangement of parts as will be hereinafter specifically described, claimed and illustrated in the accompanying drawing, in which;

Figure 1 represents a perspective view of the improved fence post, partly broken away,

Fig. 2 represents a fragmentary side elevation of the post, looking toward the side opposite that shown in Fig. 1,

Fig. 3 represents a fragmentary side elevation of the improved fence post, illustrating the locking plate in elevated position,

40 Fig. 4 represents a transverse sectional view through the fence post,

Fig. 5 represents a fragmentary side elevation of a modified type of fence post, the locking plate being removed and Fig. 6 45 represents a perspective view of the cap plate for the fence post removed.

Referring to the drawing in detail, wherein similar reference numerals designate corresponding parts throughout the 50 several views, the numeral 5 indicates the body of the post, which is formed at one longitudinal edge with a head 6, projecting laterally of the opposite sides of the body 5 and forming a reinforcing element therefor.

55 The opposite longitudinal edges of the head 6 at the lower end of the latter are beveled,

as indicated at 7, and the body 5 is also beveled at 8 to present an edge 9 to facilitate insertion of the post in the ground.

The body 5 is formed with a vertical 60 groove 10 communicating with a groove 11 formed in the head 6 and terminating adjacent the lower end of the body in a stop shoulder 12^a. The body 5 is formed at spaced points with substantially S-shaped 65 slots 12 of such width as to receive fence wires. The outer ends or throats of the slots 12 are inclined upwardly and outwardly toward the free longitudinal edge of the body 5, and the inner terminals 70 thereof are enlarged, as indicated at 13.

A locking plate 14 is slidable vertically in the grooves 10 and 11, and is securely held against displacement by the walls of the groove 11 in the head 7. The locking plate 75 14 is formed with a plurality of vertically elongated slots 15, which are arranged in line with the enlarged inner terminals of the slots 12 in the body 5 and are tapered or reduced in width from their lower to 80 their upper ends. The slots 15 in the locking plate 14 communicate with the entrance slots or throats 16, which extend through the outer edge of the plate 14 and are shaped conformably with the portions of the S- 85 shaped slots 12 in the body 5, over which they are movable, so that when the throats 16 of the slots 15 are moved into registration with the underlying portions of the slots 12 the fence wires may be inserted in 90 the slots in the locking plate and fence post. After the fence wires have been moved into the extreme inner terminals of the slots 12 and the slots 15, the locking plate 14 is moved downwardly and the wire is 95 held in the enlarged inner terminals 13 of the slots 12 and is firmly gripped or wedged between the inclined side walls of the tapered slots 15. The locking plate is locked in adjusted position with relation to 100 the post body 5 by a bolt 17 positioned through apertures 18 in the locking plate and body 5 and secured in position by a nut 19 threaded thereon. A cap plate 20 having a T-shaped recess 21 in one face thereof 105 is adapted to be slipped over the upper end of the post body 5 and head 6 during driving of the post, so that the blows delivered upon the cap plate by the tool used in setting the post will not injure the upper edges of 110 the head and body.

In the modification of the invention illus-

trated in Fig. 5, the body 5^a of the fence post is formed with the integral head 6^a and locking plate-receiving groove 10^a. The outer terminal of each fence wire-receiving slot 12^b therein is disposed horizontally and extends inwardly and downwardly toward the longitudinal axis of the groove 10, terminating in an enlarged inner terminal 13^a.

10 What I claim is:

1. A fence post including a body, a head formed integral with one longitudinal edge thereof, the head and body being substantially T-shaped in cross section, said body and head having grooves therein and the body having fence wire-receiving slots, and a slotted locking plate slidable longitudinally in the grooves in the body and head and held against lateral movement by the 20 walls of the grooves in the post.

2. A fence post including a body, a head formed integral with one longitudinal edge thereof, the head and body being substantially T-shaped in cross section, said head and body having longitudinal grooves 25 therein, and the body having fence wire-receiving slots, a transversely extending stop shoulder at the lower terminal of the groove in the body, and a slotted locking plate slidable in the grooves in the body 30 and head, movable against the shoulder and held against lateral displacement by the walls of the grooves in the post.

In testimony whereof I affix my signature in presence of two witnesses.

CHARLES C. S. EPHRAIM.

Witnesses:

C. K. INGRAM,
J. SITINJA.
